UNITED STATES PATENT OFFICE.

HENRY G. O'REILLY, OF JOLIET, ILLINOIS.

TAP FOR BARRELS.

Application filed March 17, 1924. Serial No. 699,831.

To all whom it may concern:

Be it known that I, HENRY G. O'REILLY, a citizen of the United States, residing at Joliet, in the county of Will and State of Illinois, have invented certain new and useful Improvements in Taps for Barrels, of which the following is a specification.

My invention relates to devices used for withdrawing liquids from kegs, barrels and the like and particularly to means adapted for use in withdrawing liquids by pressure from such containers.

An object of the invention is to provide a device which may be quickly and conveniently installed without the use of tools and which shall avoid the necessity for any special implements of the sort now commonly used.

In the dispensing of certain liquids under pressure it is necessary to employ a tap having the double function of an inlet and an outlet, the inlet being for the fluid under pressure and the outlet for the liquid.

In the device here disclosed I provide means whereby the frame may be securely attached to the head of the keg or barrel, projections being provided intended to underlie the chime of the keg. Mounted on the frame is a clamping device adapted to adjust itself to inequalities in the surface of the head and to be adjusted to a position over the opening in the head. When properly adjusted and clamped in position the closure or bung is displaced by the tube or conduit through which the liquid is withdrawn. The space around the conduit provides access for the fluid under pressure utilized for displacing the liquid.

The advantages described together with others not specifically mentioned will be made apparent from the accompanying description.

The invention will be more readily understood by reference to the accompanying drawings, in which—

Figure 1 is a longitudinal vertical section through a device constructed in accordance with my invention, the device being shown as applied to a keg;

Fig. 2 is a plan view of the device;

Fig. 3 is a vertical sectional view on the line 3—3 of Fig. 1;

Fig. 4 is a sectional view on line 4—4 of Fig. 1; and

Fig. 5 is a sectional view on line 5—5 of Fig. 1.

Referring more particularly to the drawings, it will be seen that I provide a frame or support consisting of a portion 10 having a diagonally arranged recess 11 therein, the purpose of which will be hereinafter described, and a portion 12 somewhat elevated with relation to the portion 10 and having a recess 13 therein. Extending downwardly from the portion 12 of the frame is a diagonally disposed projection 14, the lower terminal portions of which are of arcuate form and may be serrated, as shown. These portions are intended to underlie the chime 15 of a keg as shown in Fig. 1.

The portion 10 of the frame provides a pair of parallel guides 16 on which a slide 17 is mounted. The upper surface of the slide has a rack 18 formed thereon, while the outer extremity of the slide has an arcuate diagonally arranged portion 19 shaped to underlie a diametrically opposite portion of the chime 15. Engaging the teeth of the rack is a pivoted dog 20 arranged in a diagonal position within the recess 11 heretofore referred to. The dog is pivoted to the lower end of a screw 21 adapted to be actuated by a hand wheel 22. A detail of the form of connection between the dog and screw is shown in Fig. 4. From that view it will be seen that the screw is provided with a head 23 which engages in an undercut recess in the dog, and that because of limited lateral movement of the dog within the recess, the parts cannot become separated until the screw is advanced to a point outside of the limits of the recess. The pivot action is secured because of the play in the connection. It will be noted that the thrust of the screw through the dog on the slide is applied in the direction of outward or radial movement of the slide. It will also be noted that the slide may be extended, that is, moved outwardly radially without interference from the dog.

In view of the fact that the clamping force is secured by reason of expansive pressure applied to the staves of the keg, such force should be limited to avoid bursting of the barrel by the application of too great a force to the screw. To that end I have provided means limiting the travel of the dog relative to the slide. It will be noted that when the slide is moved outwardly to the position shown in Fig. 1, with the terminal portion beneath the chime of the barrel, the dog will rest against one of the rack teeth in a pos-

tion close to the wall 24. Thereafter when the screw is actuated the dog will travel relative to the wall or stop 24 and will contact the same after traveling a relatively short distance, thus preventing any further travel under the action of the screw. If at this time the device is not sufficiently tightly held, it is necessary to retract the screw and engage a tooth of the rack to the rear of the one formerly engaged. If the pressure theretofore exerted tending to burst the keg has been considerable, the parts will contract and return the slide to a position where it is impossible to engage another tooth. Thus I provide means preventing the possibility of bursting the keg or barrel by non-intelligent operation of the device.

The means employed for clamping the discharge conduit in position comprise a tubular member 25 having a head 26 at its lower end which may be faced with rubber 27 if desired. Connected to the tubular portion 25 is a member similar to an angle cock comprising a body portion 28 and a lateral tubular portion 29. Surrounding the portion 25 is an externally threaded sleeve 30 freely rotatable but held against longitudinal movement, by engagement at its respective ends with suitable stops. At the upper end the sleeve has projections 31 adapted as hand holds. The threaded sleeve engages with an interiorly threaded nut 32 having guideways at its sides, the top and bottom walls 33—34 respectively of the guideways, being horizontally curved or arcuate as indicated at 33', 34' in Fig. 1. These guideways, one being provided at each side of the nut, engage with guides 35 constituting part of the portion 12 of the frame and defining the sides of the recess 13 formed therein. The curvature of the sides of the guideways is to permit of any necessary oscillation of the head 26 about the nut as a center to enable it to accommodate itself to inequalities in the surface of the head 36 of the keg. The guideway likewise permits of required radial movement of the conduit as a whole to enable it to be adjusted to a position directly over the opening 37 in the head. Angular adjustment to the required position is secured by suitably positioning the lateral clamping device.

The vertical clamping action is secured by rotating the sleeve under the action of the projections 31. The employment of the rubber face for the disc 26 insures a tight fit between the head and the thrust element.

Mounted within the longitudinal aperture in the parts 25—28 is a tubular element 38 which may be connected by a hose or otherwise, to the point of withdrawal of the liquid within the keg. In order to insure a tight joint around the tubular member, I provide packing material and a gland nut 39

having lateral projections 40 for hand operation. When installing the device and assuming that the frame has been clamped in position with the thrust device over the opening 37 in the head, force is applied to the tubular member 38 to dislodge the cork or plug 41 in the opening, the cork being forced downwardly into the keg. The tubular member is then projected to the bottom of the container in the usual manner and the joint at the upper end made tight by the gland nut.

It will be noted that a space is provided around the exterior of the tubular member 38, and this space is utilized for the admission of fluid under pressure. Such fluid is supplied through the nipple 42 connected to a suitable source of supply.

The device as described may be quickly and conveniently applied and removed. In operation, it is only necessary to retract the slide 17 sufficiently to enable the lugs at the two extremities of the device to be located beneath the chime of a keg. The slide is then pushed outwardly as far as possible with the hands and the screw actuated to complete the clamping action. The next operation serves to place the thrust member 26 directly over the opening in the head and to clamp it in position. In the next operation the tubular member 38 is employed to displace the cork from the opening and after tightening the gland nut, the device is ready for use. It may be employed repeatedly without loss of liquid or injury to the barrel; it avoids the necessity for using iron ferrules or locking devices and eliminates the necessity for changing the pressure hose as is customary in the devices at present used.

Obviously the construction is capable of much modification and I do not wish to be limited except as indicated in the appended claims.

I claim—

1. In a tap for kegs, the combination of a frame having a portion adapted to underlie the chime of said keg, a slide carried thereby adapted to underlie an opposite portion of said chime, a screw carried by said frame, a dog pivoted on the screw and engaging said slide, a stop on said frame adapted to limit the travel of said dog when in engagement with said slide, and means carried by the frame for clamping a discharge conduit over an opening in said keg.

2. In a tap for kegs, the combination of a frame having a portion adapted to underlie the chime of said keg, a slide carried thereby adapted to underlie an opposite portion of said chime, a screw mounted on the frame in a position to exert a thrust on the slide in the direction of its outward travel, a dog connected to the screw and engaging the slide, the engagement of the dog with the

slide being such that the slide may be freely moved outward without interference with the dog, and means carried by the frame for clamping a discharge conduit over an opening in said keg.

3. In a device of the class described, the combination of a two-part frame, one part of the frame being provided with rack teeth, a screw carried by the other part of the frame, a dog mounted on the end of the screw with capacity for oscillation, the dog being adapted to engage with said rack teeth, the dog being mounted in a recess in said frame, the position of the dog relative to the walls of the recess being such that the section of the frame carrying the rack teeth can be projected to the extent of only one tooth under the action of said screw and dog without retracting the screw and dog for engagement with another tooth, and

means associated with the frame for effecting an outlet for liquid within the barrel.

4. In a device of the class described, the combination of a frame composed of two parts, means for effecting relative movement between the two parts to secure engagement with the chine of the barrel, one of the parts of said frame having a slot, a nut mounted for sliding engagement in said slot, a threaded sleeve engaging the interior of said nut, a head adapted to lie on the head of a barrel, over the discharge opening therefrom, the sleeve being in contact with said head, and a hand wheel for rotating said sleeve whereby relative movement between the sleeve and the nut serves to clamp the head against the head of the barrel by direct downward thrust.

HENRY GEO. O'REILLY.
